OPEN END RATCHET WRENCH

Harry G. Anderson, Alameda, Calif.

Application September 30, 1944, Serial No. 556,599

1 Claim. (Cl. 81—60)

This invention relates to mechanics' tools and particularly pertains to wrenches.

It is the principal object of my present invention to provide an improved wrench of the ratchet type which is simple in construction and efficient in operation.

It is a further object of my present invention to provide an improved ratchet wrench of the open end type in which the jaw can be readily removed and replaced to accommodate nuts or objects of different dimensions.

One form which the invention may assume is exemplified in the following description and illustrated by way of example in the accompanying drawing, in which:

Fig. 1 is a plan view of a wrench embodying the preferred form of my invention with a part of the socket thereof broken away and in section to illustrate certain details of construction.

Fig. 2 is a side elevation of the wrench.

Fig. 3 is an enlarged fragmentary view partly in section and with parts broken away to disclose the manner of mounting the jaw of the wrench in the socket thereof.

Fig. 4 is an enlarged fragmentary view in perspective showing the manner in which the cooperating ends of the latching ring and socket are formed.

Referring more particularly to the accompanying drawing, 10 indicates an open end ratchet type wrench embodying my invention. This wrench comprises an open end socket 11 having an integrally formed handle 12. The socket 11 is formed with an arcuate opening 14 which extends to approximately two hundred seventy degrees. This opening is truly concentric about a center located approximately centrally of the socket 11. At the perimeter of the opening 14 the socket 11 is formed with a latching ring groove 15 which extends completely around the socket at a point closely adjacent to one side face thereof. At the ends 16 of the socket the groove 15 is outturned for a purpose which will be hereinafter described.

Fitting within the arcuate opening of the socket and rotatable therein is an open end jaw member 17. This jaw member has a jaw opening 18 of a formation capable of receiving a nut or other object to be turned by the wrench. In this instance this jaw opening 18 is shown as to receive nuts, but, however, it is obvious it may be of other formation so as to be able to grip cylindrical objects if desired. It will be noticed that the transverse dimension of the jaw opening 18 at the throat thereof is of a dimension slightly less than

the dimension between the ends 16 of the socket 11.

The external contour of the jaw 17 is concentric to the arcuate opening 14 in the socket 11, but formed on a radius just slightly less than the radius of the opening 14. This is so that the jaw member 17 may rotate in the opening 14 of the socket 11. This external face of the jaw member 17 is formed with ratchet teeth 19 to cooperate with a pair of spring-pressed pawls 20 carried by the socket 11 at diametrically opposite sides thereof. These pawls are movable radially of the socket, but are spring-pressed into engagement with the ratchet teeth 19. Each pawl 15 is housed within a cylindrical housing 21 which is threaded into the exterior face of the socket 11 with its axis radial to the center of the socket. These pawls are offset laterally, of course, with respect to the latching ring groove 15.

Manifestly, by this construction, when the jaw 17 is engaged with a nut or other object to be turned, turning movement of the socket 11 in one direction, or in a counter-clockwise direction with reference to Fig. 1, will have no effect in turning the jaw 17 because the pawls 20 will ride over the ratchet teeth 19. However, by turning movement of the socket 11 in the opposite or clockwise direction (with reference to Fig. 1), the pawls 20, or at least one of them, will engage the ratchet teeth 19 and turn the jaw 17 in unison with the socket. Obviously by merely turning the wrench over, it may operate to turn the nut in an anti-clockwise direction.

To rotatably mount the jaw 17 in the socket 11 and to enable this jaw to be readily replaced with jaws of other sizes, I form the jaw 17 with a circumscribing external groove 15a which is complementary to the groove 15 in the socket 11. Cooperating with these grooves 15 and 15a is an arcuate latching ring 22 having inherent spring qualities so that it constantly tends to expand. This latching ring 22 is complementary to the grooves 15 and 15a and has outturned ends 23 to engage the continuations of the groove 15 in the ends of the socket 11. By pressing the ends 23 toward each other, the ring can be contracted in the groove 15a so as to be disengaged from the groove 15 in the socket, thus enabling the jaw to be removed from the opening 14 in the socket 11. While in such contracted condition, the ring and the jaw 17 can be inserted into the opening 14, and when the ring is permitted to expand into the groove 15, the jaw 17 will be effectively latched in position. In this condition the latching ring 22, as shown in Fig. 3, will serve as a

bearing member rotatably supporting the jaw 17 in the opening 14 of the socket 11.

In operation of my wrench, it is constructed and assembled as shown in the drawing and a jaw 17 having the proper size jaw opening 18 is selected. The latching ring 22 is then expanded over the perimeter of the jaw 17 and allowed to contract into the groove 15a thereof. The ring is then further contracted so that it is of a diameter to enable it to be fitted into the opening 14 of the socket 11. It, together with the jaw 17, is then inserted into the opening 14 of the socket 11 until it registers with the groove 15 in the socket. It is then permitted to expand into the socket to latch the jaw 17 therein, but permitting the jaw 17 to revolve in the opening 14 of the socket 11. When so expanded, the ends 23 of the latching ring 22 will engage the continuations of the groove 15 in the ends 16 of the socket, latching the ring 22 against rotation. The pawls 20 will engage the ratchet teeth 19 of the jaw 17, and when the wrench is turned in one direction, the socket 11 may revolve independently of the jaw 17, but when it is turned in the opposite direction, the socket 11 and the jaw 17 will turn in unison. This, of course, will enable the wrench to effectively operate as a ratchet type wrench.

In actual practice I have found a wrench constructed in accordance with my invention to be extremely efficient and extremely useful, and while I have shown the preferred form of my invention, it is to be understood that various changes may be made in its construction by those skilled in the art without departing from the spirit of the invention as defined in the appended claim.

Having thus described my invention, what I claim and desire to secure by Letters Patent is:

A wrench of the character described comprising a socket having an arcuate opening in one end thereof, said opening extending through an angle greater than one hundred eighty degrees, an open end jaw fitting within said opening and having an external perimeter formed concentrically with said opening and extending approximately through the same arc but of a radial dimension less than the radial dimension of said opening whereby it may rotate therein, the external perimeter of said jaw being formed with ratchet teeth, the adjacent peripheral faces of said jaw and socket being formed with complementary circumscribing grooves, a latching ring having inherent spring qualities adapted to nest in said grooves and removably latch the jaw in position in the socket while enabling the jaw to rotate therein, the groove in the jaw being such as to enable the latching ring to be contracted and disengaged from the groove in the socket, said ring normally tending to engage both of said grooves, a spring-pressed pawl arranged radially of the socket and projecting therethrough to engage the ratchet teeth on said jaw whereby the socket may revolve in one direction relative to the jaw but not in the opposite direction, the ends of the socket being formed with continuations of the groove therein, said latching ring being formed with outturned ends to engage said groove continuations to latch said ring in position against rotation.

HARRY G. ANDERSON.
